US00D941744S

(12) **United States Design Patent** (10) **Patent No.:** **US D941,744 S**
(45) **Date of Patent:** **** Jan. 25, 2022**

(54) **AIRCRAFT GALLEY BAY AIR VENT**

(71) Applicant: **B/E Aerospace, Inc.**, Winston-Salem, NC (US)

(72) Inventors: **Peter J. L. Burd**, Burry Port (GB); **Rohan Chalmers**, Kislingbury (GB)

(73) Assignee: **B/E Aerospace, Inc.**, Winston-Salem, NC (US)

(**) Term: **15 Years**

(21) Appl. No.: **29/719,453**

(22) Filed: **Jan. 3, 2020**

Related U.S. Application Data

(60) Division of application No. 29/622,733, filed on Oct. 19, 2017, now Pat. No. Des. 875,643, which is a continuation of application No. 15/648,359, filed on Jul. 12, 2017, now Pat. No. 10,875,649.

(57) **CLAIM**

The ornamental design for an aircraft galley bay air vent, as shown and described.

DESCRIPTION

FIG. 1 is a front perspective view of a first aircraft galley bay air vent mounted to an upper surface of an aircraft galley bay.

FIG. 2 is a front perspective view of a second aircraft galley bay air vent mounted to an upper surface of an aircraft galley bay.

FIG. 3 is a front perspective view of a third aircraft galley bay air vent mounted to an upper surface of an aircraft galley bay.

FIG. 4 is a front perspective view of a fourth aircraft galley bay air vent mounted to an upper surface of an aircraft galley bay.

FIG. 5 is front perspective view of the aircraft galley bay air vent of FIG. 1 illustrating an oven inserted in the aircraft galley bay; and,

FIG. 6 is a front perspective view of the aircraft galley bay air vent of FIG. 3 illustrating an oven inserted in the aircraft galley bay.

The broken lines in the drawings illustrate environmental subject matter and form no part of the claimed design.

1 Claim, 6 Drawing Sheets
